UNITED STATES PATENT OFFICE.

ROBERT J. HEWETT, OF WESTFIELD, NEW JERSEY, ASSIGNOR TO THE HALL SIGNAL COMPANY, A CORPORATION OF MAINE.

LOCK AND BLOCK SIGNAL SYSTEM

Specification of Letters Patent Patented Dec. 15, 1908

Application filed January 10, 1908. Serial No. 410,277

To all whom it may concern:

Be it known that I, ROBERT J. HEWETT,
a citizen of the United States, residing at
Westfield, in the county of Union and State
5 of New Jersey, have invented a certain new
and useful Improvement in Lock and Block
Signal Systems, of which the following is a
specification, reference being had therein to
the accompanying drawings, forming part
10 thereof.

10 *invention relates particularly to electrically-controlled manually-operated signal lock-and-block systems for use in connection with single-track railways, but it embodies*

One object of the invention is to produce a signal system in which a track circuit and track battery are used and in which a high degree of economy in the use of the track battery is secured, and to this end the invention comprises a system in which the track battery is normally inactive, and in which the track battery, after being thrown into circuit is again thrown out of circuit immediately upon the entrance of a train to the block, so that the battery is short-circuited only for the instant required for the operation of the electrical apparatus, and is in operation only in the short interval of time between the release of a signal and the entrance of a train to the block.

Another object of the invention is to produce a system in which cut-section track-circuit repeaters are so arranged, in connection with the route circuit as to set up automatically a track circuit in the right direction according to the direction in which a signal release is transmitted.

40 Other objects and features of the invention will be noted in connection with the description of the illustrated embodiment of the invention.

I will now describe the embodiment of my invention illustrated in the accompanying drawing and will thereafter point out my invention in claims.

The drawing is a diagram of a single-track, electrically-controlled, manually-operated, 50 lock-and-block signal system.

The rails 1 and 2 of the single track form parts of a track circuit, and they are divided and insulated at points 3 at the ends of the block, and at one or more intermediate points. Two stations, designated as "Sta-

tion A" and "Station B" are represented in the diagram and the apparatus involved in the mutual operations of these stations is shown, while the apparatus by which each station coöperates with the next station beyond is omitted, as it is merely a duplication of the apparatus shown.

Each station is provided with a west-bound signal 5, and an east-bound signal 6. The signals are of the normal-danger type, and are electrically controlled by a controlling device 7. This device may be an electric slot, in which case it will be applied directly to the signal post as shown, or an electric lock applied in the usual manner to the signal-operating mechanism, or it may be a signal-actuating device. In any case the essential characteristic is the fact that the signal cannot be set or maintained at safety position except when the electric control device is energized.

To prevent interference between trains moving in opposite directions each signal is provided with a circuit breaker 8 connected directly with the semaphore or the semaphore rod. These circuit breakers are included in the route circuit and are closed when the signals are at danger position. 80

Each station is provided with a track relay 9, which is included in the track circuit 85 and controls contact fingers 10. A signal-circuit relay 11 controls a release-indicator 12 which indicates when the signal has been released, and a contact finger 13, normally open, by which the signal-releasing circuit 90 is finally established. A route-circuit relay 14, energized by the closing of the route-circuit, controls contact fingers 15, and an indicator 16 which indicates the closing of the route-circuit to transmit a release, and is also 95 preferably provided with a back-stroke bell 17 for a purpose to be referred to later.

The manual control of the electrical apparatus is effected by a plunger circuit closer 20. When the plunger is pulled it closes one 100 circuit and assists in the transmission of a release, and when it is pushed it closes another circuit and assists in the reception of a release. It is normally held in neutral inoperative position by a spring or other suitable 105 arrangement.

The stations are connected by a normally-open route-circuit comprising route wires 22 and 23, and the operators communicate with each other by means of telephones 24 which 110

are bridged across the route-circuit through condensers 25.

The apparatus at the track-circuit cut-section is primarily controlled by a polarized relay 26 included in the route-circuit. This relay has two polarized contact fingers 27, which move to the right or the left according to the direction of the current in the route-circuit, and two neutral contact fingers 28 which close their circuits whenever the relay is energized. Track relays 29 and 31 and track batteries 33 and 34 are connected with the rails and controlled by the polarized relay. A condenser 35 bridges the relay 26 to avoid resistance in the operation of the telephones.

The circuits connecting the apparatus above referred to can be described most conveniently in connection with the description 20 of the operation of the apparatus.

When an operator at either station wishes to set his incoming signal to safety to admit a train to the block he must secure a release of his signal or signal-operating mechanism 25 by the slot 7, and for this the conjoint action of the operators at both ends of the block is necessary. The electrical operations by which a release is effected involve three distinct steps. The first step is the establishment 30 of the route-circuit by the action of the operators, the second step is the automatic establishment of the track circuit resulting from the establishment of the route-circuit, and the third step is the establishment of a 35 local circuit through the slot resulting automatically from the establishment of the track circuit.

The operation of the apparatus will now be more specifically described. Suppose the 40 operator at A wishes to set his incoming signal 6 at safety to admit an east-bound train to the block A—B. He communicates with operator B by telephone, and if everything is clear the operator B pulls his plunger 20, 45 while operator A pushes his plunger. The route-circuit is now established as follows: from station battery 21, at station B, by wires 38 and 39, to the magnet of relay 14, 50 thence to pull-contacts 40 of plunger 20, which are now connected by the pulling of the plunger, thence, through wire 41, to a normally-closed contact finger of track relay 9, thence to the circuit breaker 8 on signal 5, 55 thence by wires 42 and 43, to the circuit breaker 8 on signal 6, and thence by wire 22, through the magnet of relay 26, and on by the wire 22 to station A; at station A the circuit passes through the circuit breaker 8 on signal 5, thence, by wires 44 and 45, to the 60 push contacts 46 of plunger 20, thence, by wire 47, to the magnet of a relay 18, and thence back to station B by a wire 48 and the route wire 23.

The energization of the route-circuit relay 65 14 at station B has three immediate effects.

The indicator 16 moves to indicate the completion of the route-circuit, a stick circuit is established through the relay, and the local track battery 36 is thrown into circuit with the track. The stick circuit passes through 70 one of the contact fingers 15, which has been raised to engage a front contact, and thence, by wire 49, directly to wire 41, thereby bridging the plunger 20, so that the movement of the indicator 16 notifies the operator that he may release his plunger without breaking the circuit.

The track circuit established by the relay 14 at station B passes from the track battery 36, by wire 50, to a back-contact and contact 80 finger 19 of a normally deenergized relay 18, thence, by wire 51, to the second contact finger of relay 14, thence, by wire 52, to contact finger 10 of track relay 9, and thence, by wire 53 and rail 1, to cut-section 4. Here 85 the relay 26 has already been energized, by the closing of the route-circuit through wire 22, so that contact fingers 28 are in closed position, and contact fingers 27 are in right-hand position as shown in the drawing. From 90 rail 1 the track circuit passes through the wire 54, a contact finger 28, wire 55, a contact finger 27, wire 56, the magnet of relay 31, wire 57, and rail 2, and thence, at station B, by wires 58 and 59, back to battery 36. 95

The energization of the relay 31 causes the contact finger 32 to close, and thereby completes the track circuit through the magnet of the track relay 9 at station A. This circuit proceeds from track battery 33, at the 100 cut-section, by wire 61 to rail 2, thence, at station A, by wire 62 to the magnet of track relay 9, thence through a manual circuit-breaker key 63, to be referred to later, thence, by wire 64, to a contact finger 19 of relay 18, 105 which has previously been raised to engage a front contact by the closing of the route-circuit through the relay 18, thence, by wire 65, rail 1, and wire 66 at the cut-section, to contact finger 28, thence, by wire 67, to contact 110 finger 27, by wire 68, to contact finger 32, and thence back to battery 33.

The second step in the operation of the apparatus is now completed, and the third step results from the energizing of track relay 9 115 at station A. Contact fingers 10 are raised and have two immediate operations. One of these is to close a branch circuit through wire 69 by which the plunger 20 is bridged, so that the operator may release the plunger 120 without breaking the route-circuit. The other operation of the contact fingers 10 is to complete a local circuit through the signal-circuit relay 11. This circuit is from battery 21, at station A, through wire 71, the 125 magnet of relay 11, wire 72, contact finger 10, wire 73, wire 74 and wire 23 back to the battery. Relay 11 thereupon transmits releasing current to the signal by a branch from wire 71 by way of the contact finger 13 and 130

wire 75, and from the slot 7 the circuit returns through wires 74 and 23 to battery 21. The relay also moves the indicator 12, which notifies the operator that he may release his plunger and set the signal.

The apparatus remains in the condition described until the train enters the block, but as soon as this occurs the apparatus is returned at once to normal condition as a result of the short-circuiting of track relay 9 by the train. The effect of this is to release contact fingers 10, thereby allowing them to fall and interrupt the stick circuit of the relay 18 through wire 69. The route-circuit being thus broken all the relays are deenergized and the apparatus returns to normal condition.

As long as the train remains in the block a release cannot be transmitted in either direction, as the train short-circuits the track relays. The entrance of the train to the block is signaled to the operator at B, upon the deenergization of relay 14, by an audible signal on the bell 17 and by the return of indicator 25 to normal position, and it now becomes the duty of the operator to communicate with the operator at the next station to the east in order to secure a release of his signal 6.

If the next communication between stations A and B is a release in the same direction as before the polarized contact fingers 27 of relay 26 remain in right-hand position, but if a release is to be transmitted from station A to station B to admit a west-bound train, the current in the route-circuit is opposite to its first direction of flow, and contact fingers 27 are reversed, so as to put the cut-section apparatus into condition to establish a track circuit from battery 34 to station B. The operation of the station apparatus is, in such a case, in all respects analogous but opposite to the operation in transmitting a release from B to A.

The contact fingers of the track relays 9, in addition to contributing to the normal operation of the apparatus in the ways hereinbefore described, are also included both in the track circuit from battery 36 and in the route circuit. This is not essential to the operation of the apparatus, but is merely a safeguard to prevent the transmission of releases in both directions at once and the possible entrance of two trains at once into the block from opposite directions.

In some cases it may be desirable, after a release has been secured, to return the apparatus again to normal condition, as, for example, when a train expected to enter a block is diverted or sent back so as not to enter and release the apparatus in the normal manner. For this purpose the manual recall key 63 is provided. By depressing this key the circuit through the track relay 9 is interrupted, with the same effect as when the relay is short-circuited by a train.

The system has a high safety factor, owing to the fact that the transmission of a release requires the mutual action of the operators, the proper operation of the route-circuit apparatus, the track-circuit apparatus and the signal-circuit apparatus, and the entire absence of rolling stock from the block. The signals automatically return to danger immediately upon the entrance of a train to the block and cannot be set clear in either direction until the train has passed entirely from the block. As all batteries are normally inoperative the current consumption is very small, and the reliability of the system is increased.

It is obvious that various modifications may be made in the system hereinbefore described and illustrated in the drawing within the nature and scope of the invention as defined in the claims.

I claim:

1. An electric lock-and-block signal system comprising a signal, an electric signal-controlling device, a route circuit connecting two signal stations, a track circuit, means for closing the route circuit, means operating automatically upon the closing of the route circuit to close the track circuit, and means operating automatically, upon the closing of the track circuit, to operate the signal-controlling device to release the signal.

2. An electric lock-and-block signal system comprising a signal, an electric signal-controlling device, a route circuit connecting two signal stations, manually-operable means for closing the route circuit, means operating automatically, upon the closing of the route circuit, to close the track circuit, and means acting automatically, upon the closing of the track circuit, to operate the signal-controlling device to release the signal.

3. An electric lock-and-block signal system comprising a signal, an electric signal-controlling device, a route circuit connecting two signal stations, a track circuit, manually-operable means at both stations operable simultaneously to complete the route circuit, means operating automatically, upon the closing of the route circuit, to close the track circuit, and means acting automatically, upon the closing of the track circuit, to operate the signal-controlling device to release the signal.

4. An electric lock-and-block signal system comprising a signal, an electric signal-controlling device, a route circuit, a continuous track circuit, normally open, automatic means for closing the track circuit upon the closing of the route circuit, means acting automatically, upon the closing of the track circuit, to operate the signal-controlling device to release the signal, and means operating automatically to open the track circuit when a train enters the block.

5. An electric lock-and-block signal sys-

tem comprising a signal, an electric signal-controlling device, a route circuit, normally open, connecting two signal stations, a continuous track circuit, normally open, means 5 for closing the route circuit, means operating automatically, upon the closing of the route circuit, to close the track circuit, means acting automatically, upon the closing of the track circuit to operate the signal-controlling 10 device to release the signal, and means operating automatically to open the track circuit and the route circuit when a train enters the block.

6. An electric lock-and-block signal system comprising a signal, an electric signal-controlling device, a route circuit, normally open, connecting two signal stations, a continuous track circuit, normally open, manually-operable means for closing the route circuit, means operating automatically, upon the closing of the route circuit, to close the track circuit, means acting automatically, upon the closing of the track circuit, to operate the signal-controlling device to release the signal, and means operating automatically to open the track circuit and the route circuit when a train enters the block.

7. An electric lock-and-block signal system comprising a signal, an electric signal-controlling device, a route circuit, normally open, connecting two signal stations, a continuous track circuit, normally open, manually-operable means at both stations operable simultaneously to complete the route 30 circuit, means operating automatically, upon the closing of the route circuit, to close the track circuit, means acting automatically, 35

upon the closing of the track circuit, to operate the signal-controlling device to release the signal, and means operating automatically to open the track circuit and the route circuit when a train enters the block.

8. An electric lock-and-block signal system comprising a continuous track circuit provided with a cut section, a track battery at 40 one end of the track circuit for energizing the track circuit to the cut section, a battery at the cut section for energizing the track circuit from the cut section to the other end of the block, a route circuit connecting the signal stations, and a relay at the cut section interposed in the route circuit and operating to control the track circuit from the cut section to the end of the block.

9. An electric lock-and-block signal system comprising a continuous track circuit provided with a cut section, track batteries at 45 the ends of the block for energizing the track circuit to the cut section, track relays and batteries at the cut section for energizing the track circuit from the cut section to the ends of the block, a route circuit connecting the signal stations, and a polarized relay at the cut section interposed in the route circuit and connected with the track relays so as to operate to determine, according to the direction of the current in the route circuit, the direction of operation of the track relays.

In testimony whereof I affix my signature in presence of two witnesses.

ROBERT J. HEWETT.
